DESIGN.

A. HEALD.

Carpet-Patterns.

No. 7,138.

Patented Jan. 27, 1874.

UNITED STATES PATENT OFFICE.

ALFRED HEALD, OF PHILADELPHIA, PENNSYLVANIA, ASSIGNOR TO HUGH McCALLUM, ORLANDO CREASE, ANDREW J. SLOAN, AND WM. McCALLUM, OF SAME PLACE.

DESIGN FOR CARPET-PATTERN.

Specification forming part of Design No. 7,138, dated January 27, 1874; application filed January 10, 1874.
[Term of Patent 3½ years.]

L.

To all whom it may concern:

Be it known that I, ALFRED HEALD, of the city and county of Philadelphia, State of Pennsylvania, have produced or invented a Design for a Carpet-Pattern, of which the following is a specification:

The accompanying drawing shows sufficient of the pattern to illustrate my design, the main features of which are the figures A, B, C, and D.

The oblong figure A occupies the center of the pattern, has a central foliated ornament, *a*, and is surrounded by a wreath of leaves, *b*. The figures B are diamond-shaped, and are defined by deep borders *d*, and from the central circular ornament *e* of each of the figures radiate four oblong arms, *f*, which cross and interrupt the continuity of the borders *d*. The figure C has a comparatively plain border, *g*, and a foliated ornament, *h*, in the center, and opposite each corner of the said figure are flowers, leaves, and stems *i*, arranged as shown. The figure D is the most elaborate of the series. It has a square central ornament, *j*, from the corners of which radiate scrolls *k* and a

square border, *l*, the latter being curved at the center of two of its opposite sides to conform to the shape of an elaborate ornament, *m*, consisting of scroll-like leaves and fruit, all arranged in a manner too clearly shown in the drawing to need minute description. The remaining two sides of the border of the figure are crossed by foliated ornaments *p*.

Irrespective of the colors employed, I claim—

1. The design for the figure A, as shown and described.
2. The design for the figure B, as described and represented.
3. The design for the figure D, as illustrated and described.
4. The design for the whole pattern, including the figures A, B, C, and D.

In testimony whereof I have signed my name to this specification in the presence of two subscribing witnesses.

ALFRED HEALD.

Witnesses:

W.M. A. STEEL,
J. SHERBORNE SINGER.
